STOOL

Jerry J. Hammond, Wright Township, Ottawa County,
Mich. (14891 8th Ave., Marne, Mich. 49435)
Filed Mar. 3, 1966, Ser. No. 531,542
1 Claim. (Cl. 108—156)

This invention relates to stools. The main objects of this invention are:

First, to provide a stool which is well adapted for use by children and is capable of withstanding severe usage such as, for example, dropping or throwing.

Second, to provide a stool having these advantages which is economical to produce and one which is relatively light in weight in proportion to its load supporting capacity.

Third, to provide a stool in which the legs are effectively but detachably connected to the body so that the stool may be compactly arranged for shipment or storage and may be quickly and easily set up without the use of tools.

Fourth, to provide a structure having these advantages in which parts do not warp or become out of shape.

Fifth, to provide a structure having all of these advantages which may be economically produced.

Additional objects and advantages of the invention will be apparent to persons acquainted with devices of the type upon reading the following description and inspecting the accompanying drawings, in which:

FIG. 1 is a perspective view of the stool embodying my invention with portions broken away to show structural details.

FIG. 2 is a front elevational view of the stool embodying the invention.

FIG. 3 is an enlarged fragmentary view partially in section on a line corresponding to line 3—3 of FIG. 2.

In the embodiment of my invention illustrated, the body portion 1 is rectangular but it should be understood that it may be circular, oval, or any other shape. That is, that the parts and the assembling thereof permit the variation in shape. The body member 1 is of molded construction, preferably being of molded wood chips, such as conventional chipboard. The body member 1 is substantially uniform in thickness throughout, does not warp and is extremely difficult to crack or fracture. Bores 2 are spaced inwardly from the corners of the body member 1, there being recesses 3 in the upper side of the body member surrounding these bores 2. Internally threaded leg coupling members 4 are fittingly disposed in these bores and they are provided with outwardly projecting flanges 5 on their upper ends which flanges are received within the enlarged recesses 3. These flanges 5 have downwardly projecting lugs 7 which are embedded in the body member thereby preventing rotative movement of the coupling members.

Legs 8 are desirably formed of wood and have flat upper ends 9 of substantial diameter disposed in supporting engagement with the underside of the body member 1. The leg attaching members 10 are of substantial length and project into the legs, tight threaded engagement being desirable, and is conventionally illustrated at 11. These leg attaching members 10 are disposed centrally to the legs and have threaded projecting portions 12 which have threaded engagement with the coupling members 4 which are, as stated, nonrotatably secured to the body member thus attaching the legs to the body member 1. The legs

thus may be quickly engaged with or disengaged from the tubular coupling members fixedly mounted on the body member. In the particular embodiment shown, the leg attaching members are hanger bolts.

A relatively thin unitary top panel 14 is dimensioned to correspond to the body member, as is illustrated in the drawings, and completely covers the body member and is adhesively secured, as indicated at 15, to the body member. The top panel is relatively hard and tough and provides a durable covering for the body member 1. In addition, the top panel locks the coupling members 4 rigidly in the body member 1. In this embodiment of my invention, the top panel is of a molded fiber material widely known as Masonite and has a textured under surface well adapted to a strong adhesive bond.

In the embodiment illustrated, a finish layer 16 is illustrated but is desirably of such character that it does not appear in the assembled structure and it is illustrated in the drawings merely to illustrate a complete embodiment of my invention. The opposed faces of the top panel and body member have such texture as to receive a substantial amount of the adhesive so that the top panel is secured to the body member without the necessity of using screws or similar attaching devices and a perfectly smooth outer surface on the top panel is provided which is desirable from the use and the appearance standpoints.

The legs are desirably provided with bottom pieces 17 secured thereto by the nails 18 and serves the double purpose of substantially eliminating the sliding of the stool on a smooth surface and also in preventing noise when the stool is set on a hard surface while preventing marring of such surfaces.

It is desired to point out that the embodiment of my invention illustrated may be economically produced both in material and the forming and assembling of the elements. The embodiment illustrated, in which the top portion is rectangular, is a desirable structure but it may be other shapes, for example, round and all of these varying shapes may be economically produced both from the angle of material and the assembling thereof.

When the legs are removed, there are no projections on the body portion so that the structure may be quite compactly arranged, the legs being placed sideways against the body member and the legs may be quickly attached to the body unit without the use of tools, which, as stated, is highly desirable when viewed from the several stated angles.

Although a particular preferred embodiment of the invention has been disclosed above for illustrative purposes, it will be understood that variations or modifications thereof which lie within the scope of the appended claim are fully contemplated.

Having thus described the invention, what is claimed as new and desired to secure by Letters Patent is:

A stool comprising:

a one-piece rigid body member of substantially uniform thickness having substantially flat parallel top and bottom surfaces, said body member being molded of particulate material so as to have high strength and toughness, said body member having a plurality of laterally spaced openings therethrough, said body member having enlarged annular recesses formed in the top surface thereof and surrounding the upper ends of said openings, said recesses extending only partway through said body member;

internally threaded, tubular, leg coupling members snugly received within and extending through said openings, said leg coupling members having enlarged annular flanges at their upper ends disposed in said recesses and a plurality of downwardly projecting lugs embedded in the bottom walls of the recesses and securing said leg coupling members against rotation with respect to said body member;

a plurality of legs connected to said body member, the upper portion of said legs being of larger size than said openings and having integral shoulder means supposedly engaging the bottom surface of said body member;

attaching means for said legs fixedly secured thereto and having externally threaded portions projecting upwardly from the upper ends of said legs, said threaded portions extending into and being threadedly engaged with said coupling members for fixedly interconnecting said legs and said body member; and

a one-piece thin panel of form retaining material adhesively secured to the top surface of said body mem-

ber, said panel and said body member being coextensive in shape and size such that said panel covers the upper ends of said openings and recesses.
